FILM PROCESSOR DRYING CONTROL

John W. Gillon, Hartsdale, N. Y., assigner to General Precision Laboratory Incorporated, a corporation of New York

Application January 4, 1951, Serial No. 204,361

8 Claims. (Cl. 34—48)

1

This invention pertains to controls for photographic film developing processors, and more specifically to controls for the drying operation in motion picture film processing.

It is especially necessary to control the film drying process accurately in rapid film developing processes such as are used in recording television programs for either immediate and/or subsequent projection. In such processes the entire processing of the film including developing, fixing, washing and drying is accomplished in a minute or less, with only fifteen seconds of this time allotted for drying the film. At the same time the film must be effectively dried so that it may be used immediately for projection.

The mechanism of a rapid processor in general consists of a light-tight cabinet having in succession separate chambers for developing, rinsing, fixing, washing and drying the exposed film. The film is fed from a supply reel or directly from the camera and is threaded over a series of rollers which continuously pass the film through the successive developing, rinsing, fixing, washing and drying chambers. From the drying chamber other rollers pass the film either to storage reels or directly to a projector. When the film is fed directly from a camera to the rapid processor and directly therefrom to a projector the rate of travel through the processor must necessarily be that of travel through the camera and projector, which is 24 frames per second for sound film, and in the case of 16 mm. film is 0.6 feet per second.

It is very desirable to keep the time of film travel through the processor as short as possible, and to keep the physical dimensions of the processor small. To do so when the film travel rate is so high requires that the efficiency of the film-drying component of the processor be high. In the present invention infra-red drying is employed with the vapor-laden air removed by suction.

The speed of drying of any particular section of a developed motion picture film strip depends upon the amount and length of time the infra-red energy is directed upon it, the speed of air scavenging and finally upon the film opacity or transparency. Dense film intercepts a greater proportion of the infra-red energy radiated toward it, converting it into sensible heat which in turn raises the temperature of the film and the vapor pressure of the moisture contained in the gelatine thereon and supplies the latent heat for vaporization thereof. Completely transparent film, on the other hand, intercepts only a small

amount of radiant energy impinging upon it, so that the drying effect produced thereon is much less than the drying effect produced by the same amount of infra-red energy impinging on completely exposed film which has the maximum possible opacity.

In designing a rapid process drying compartment it is not possible to apply enough heat to dry transparent film in the time allotted without overheating dense film, resulting in the gelatine being crinkled or even in being completely melted from the denser parts of the film. On the other hand, if only sufficient radiant heat is applied to the film to dry the dense portions the transparent portions will not be thoroughly dried and when reeled the still damp film may stick and droplets of water remaining thereon may cause spotting.

In order to overcome this problem the instant invention monitors the developed film before it enters the drying compartment to ascertain its density or transparency and adjusts the applied quantity of infra-red radiation accordingly. The monitoring operation is accomplished by means of a light-sensitive device placed on one side of the moving film and a small light source placed on the other side thereof, so that the output of the light-sensitive device is a measure of film transparency. The source of infra-red radiation consists of two sets of incandescent heat lamps, a regular group and an auxiliary group. The regular group has an intensity sufficient to dry film whose density is above a selected amount, and the auxiliary group of lamps when combined with the regular set provides an increased aggregate intensity sufficient to dry transparent film. The regular group is operated continuously and the auxiliary group is turned on by a signal derived from the light-sensitive source when the film density is below the above mentioned selected amount.

Since any film section takes about 15 seconds to pass through the drying compartment, any transparent portion, even if short, should be exposed to the necessary increased heat radiation for such length of time as to insure its being thoroughly dried. This requires the addition of a time delay element so that, after the auxiliary group of lamps has been turned on, it will remain on for the desired time, which may be the time required for the transparent element to complete its passage through the dryer or may be less, after which the auxiliary group of lamps will be turned off. If, however, during the passage of the transparent element through the

dryer, another transparent element should enter the monitoring section, the auxiliary group control equipment is automatically reset so that the additional lamps are not turned off until the later transparent element has passed through the dryer.

In order to prevent the accumulation of heat energy in the drying compartment with a consequent destructive temperature increase, all surfaces therein are made highly specular and as non-absorptive as possible. In addition a safety cutoff may be provided.

The general object then of this invention is to provide motion picture film drying equipment which discriminates between film sections the density of which is greater or less than a pre-selected value.

More specifically, the object of this invention is, in a film processing machine, to control the application of radiant drying heat to the film in accordance with its relative transparency.

Another object of the invention is, in a motion picture film rapid processing machine, to increase the quantity of infra-red energy applied to the film when the film is more transparent to such energy than a preselected amount, and to decrease the quantity of infra-red energy applied when the film is less transparent than such pre-selected amount.

A further understanding of this invention may be secured from the detailed description together with the accompanying single drawing figure in which the mechanical arrangement and the electrical circuit are schematically depicted.

Referring now to the single figure, a rapid film processor is provided with a drying compartment 11 for drying a motion picture film strip 12 delivered to it from a preceding washing compartment. The film strip is passed from an entrance tunnel 13 through a monitoring cell 14, to be described later, thence through a narrow exit slit 15 and tube 15' acting as a light exclusion trap, into the drying chamber 11, where the film is passed over a series of upper rollers 16 and lower rollers 17 having a capacity of say nine feet of film. In leaving the last roller 18, the film is withdrawn from the compartment through a slit 19 to be either wound on a storage reel or fed directly to a projector.

During the interval in which the film strip is encompassed in the drying chamber it is irradiated by heat rays derived from one or more infrared lamps, six of which, 21, 22, 23, 24, 25 and 26 are shown in the figure. These lamps are divided into two groups. The first or regular group may consist of any desired number of lamps, it being required only that the intensity of radiation from this group shall be adequate to dry film of average density or opacity. In the figure this group is represented by a single lamp 21 which is continuously energized from a standard power source through the medium of conductors 27 and 28. The second or auxiliary group consists of lamps 22 to 26 having an aggregate power that in general will be several times that supplied by the regular group, their power being sufficient in combination with the power of the regular group to dry completely transparent film during all or a selected fraction of the travel of such a film section through the chamber. These auxiliary lamps are connected in parallel with each other and to a 115-volt power source in series with suitable control equipment, so that they are energized only during the time that a transparent or

low density section of film is traveling through the chamber.

The control equipment consists first of a monitoring source of light 29 contained in the monitoring cell 14. The light 29 may conveniently be an ordinary small neon lamp or a stroboscopic neon lamp operated from the usual power mains. The lamp 29 is placed on one side of the film strip 31 so that the light emitted thereby falls on the film strip 12 as it is drawn through the monitoring cell. The degree of transmission by any portion of the exposed film strip of the variations emitted by the neon lamp is approximately the same as the degree of transmission by the same portion of film strip as respects infra-red radiation, so that the amount of neon light illumination passed by a portion of film in the monitoring cell 14 is a measure of the amount of infra-red which will be transmitted by the same portion later as it passes through the drying chamber, and such transmission characteristic is an inverse function of the amount of radiation absorbed and hence its drying effect. Since the neon lamp is energized from a 60-cycle source, the resulting light produced thereby is modulated at a 120 C. P. S. rate. The fraction of this modulated light which is passed through the film 31 is directed onto the cathode 32 of a gas phototube 33, the anode 34 of which is energized from a well-filtered direct-current source represented by terminal 36 having an additional filter represented by resistor 37 and condenser 38. A load resistor 39 is connected in series with the phototube anode 34 and its source 36, a small condenser 41, of say, 500 M. M. F. capacity, being connected to the anode terminal 42 to filter out any high frequency components which may be present. The 120-cycle modulation component of the light produces a variation of the internal impedance of the phototube at the same frequency having an amplitude proportional to the degree of light transmission of the film 31. This impedance variation produces a corresponding variation of current in the load resistor 39 and of voltage at the terminal 42.

The 120-cycle voltage variation existing at terminal 42 is applied through a condenser 43 to the control grid 44 of an amplifier tube 46, to produce an amplified alternating voltage at the anode terminal 47. The tube 42 may be followed by any desired number of amplifier stages, but for purposes of illustration the tube 42 is shown as coupled through conventional condenser coupling to the final amplifier stage comprising a thyratron 48. The tube 48 has its anode energized by a 60-cycle alternating current supply so that the current therethrough falls to zero every cycle. The grid bias therefor is supplied in the usual way so that a very small plate current flows in the absence of an input signal. The input signal is applied to the control grid 49 in such phase relation as to produce an anode current of a magnitude representative of the input signal intensity. The cathode 51 is grounded through a relay coil 52 shunted by a condenser 53, resulting in an average direct current flow in the coil representative of input signal intensity.

Associated with the relay coil 52 are contacts 54 having a pick-up value representing a definite input signal intensity, which in turn represents the degree of film heat transmission at which it is desired to energize the auxiliary group of infrared lamps. The contacts 54 when closed energize

the coil 55 of a time delay relay 56 having instantaneous pick up and delayed release. The relay 56 is of the plunger type having an iron armature 57 connected by a brass rod 58 with a contact cross piece 59. When the coil 55 is energized the armature 57 is pulled up, the cross piece 59 closes the circuit between two fixed contacts 61 and 62, and the internal follow spring 63 is compressed until the armature 57 is prevented from further movement by a stop 64. As the armature 57 travels upward it draws with it a piston 66 to which it is connected by a rod 67, the piston 66 working in a dashpot 68 filled with oil. The piston 66 is designed to move upward unimpeded by the oil but moves downward under the combined weight of the armature and the pressure of spring 63 only as fast as the oil is permitted to flow through an adjustable orifice 69, the expanded piston leather 71 preventing leakage between it and the cylinder wall. As the piston falls, the cross piece 59 breaks contact with the fixed contacts 61 and 62, the time of fall to break being adjustable between one and fifteen seconds by means of the adjustable orifice 69.

When the contacts 61, 62 are connected by the contact cross piece 59, a circuit is closed which includes the power supply conductors 72, 72 and a load consisting of the auxiliary lamp group composed of lamps 22, 23, 24, 25 and 26. These lamps are therefore energized as soon as the relay 56 is closed and remain energized until the end of the opening time delay period. If, during the relay time delay period the relay should again be energized, as by a second section of highly transparent film passing between the lamp 29 and cell 33 the armature 57 is again drawn upward and the full time delay period is reinitiated.

If a short length of say, one foot of nearly transparent film should be succeeded after almost nine feet of opaque film and then by another short length of nearly transparent film, the auxiliary lamp bank would be kept burning continuously. Under such circumstances the incidental heat storage in the walls and air of the drying chamber are liable to cause such a rise of temperature in opaque portions of film as to endanger them. In order to provide against such a contingency a bimetallic thermostat 73 is provided having one side of its bimetal strip blackened so as to be exposed to the same degree of temperature rise under infra-red radiation at any selected degree of ambient temperature as opaque or very dense film strip. The thermostat 73 is positioned for exposure to the auxiliary lamp radiation, and its contacts 74 are connected in series with the auxiliary lamp circuit, so that a sustained degree of infra-red irradiation which would be liable to endanger the film results in the opening of the auxiliary lamp circuit. At the same time, the thermostat automatically restores the circuit when it and the film have cooled to a safe temperature.

What is claimed is:

1. In a motion picture film processor, an apparatus for drying a moist developed motion picture strip comprising, a drying chamber, means contained therein for supporting said motion picture strip as it is passed therethrough, a source of continuously energized heat radiation in said drying chamber positioned to direct heat rays on said film strip, means associated with said film strip for ascertaining the density thereof, an auxiliary source of heat radiation in said drying chamber, a circuit for energizing said auxil-

iary source, switch means in said circuit controlled by said means for ascertaining the density of said film strip, and means associated with said switch means for maintaining said switch means closed for a predetermined time after actuation thereof.

2. Apparatus as defined in claim 1 in which said means for ascertaining the density of said film strip comprises a light source and a phototube positioned on opposite sides of said film strip.

3. In a motion picture film processor, an apparatus for drying a moist developed motion picture strip comprising, a drying chamber, means contained therein for supporting said motion picture strip as it is passed therethrough, a normally energized infra-red source positioned to project infra-red rays developed thereby on said film strip, means located adjacent the point of entry of said film strip into said drying chamber for ascertaining the average density of said film strip, an auxiliary infra-red source positioned in said drying chamber, a circuit for energizing said auxiliary source, switch means in said circuit controlled by said means for ascertaining the density of said film strip and means associated with said switch means for abruptly closing and delaying the opening thereof.

4. Apparatus as defined in claim 3 in which said means for ascertaining the average density of said film strip comprises a light source and a phototube positioned on opposite sides of said film strip.

5. In a motion picture film processor, an apparatus for drying a moist developed motion picture strip comprising, a drying chamber, means contained therein for supporting a predetermined length of said motion picture strip as it is passed therethrough, a source of continuously energized heat radiation in said drying chamber positioned to direct heat rays on said film strip, means associated with said film strip for ascertaining the density thereof, an auxiliary source of heat radiation in said drying chamber, a circuit for energizing said auxiliary source, switch means in said circuit controlled by said means for ascertaining the density of said film strip, means associated with said switch means for maintaining said switch means closed for a predetermined time after actuation thereof, and additional circuit interrupting means connected in said circuit and located in said drying chamber for interrupting said circuit when the ambient temperature of said chamber exceeds a predetermined limit.

6. Apparatus as defined in claim 5 in which said means for ascertaining the density of said film strip comprises a light source and a phototube located on opposite sides of said film strip.

7. In a motion picture film processor, an apparatus for drying a moist developed motion picture strip comprising a drying chamber, means contained therein for supporting said motion picture strip as it is passed therethrough, a normally energized infra-red source positioned to project infra-red rays developed thereby on said film strip, means located adjacent the point of entry of said film strip into said drying chamber for ascertaining the density of said film strip, an auxiliary infra-red source positioned in said drying chamber, a circuit for energizing said auxiliary source, switch means in said circuit controlled by said means for ascertaining the density of said film strip, means associated with said switch means for abruptly closing and delaying

75 the opening thereof, and additional circuit inter-

rupting means connected in said circuit and located in said drying chamber for interrupting said circuit when the ambient temperature of said chamber exceeds a predetermined limit.

8. Apparatus as defined in claim 7 in which said means for ascertaining the density of said film strip comprises a light source and a phototube located on opposite sides of said film strip.
